Primary Examiner — Kelley A Donnelly*(74) Attorney, Agent, or Firm* — Dority & Manning, P.A.(57) **CLAIM**

The ornamental design for a foldable utility enclosure, as shown and described.

DESCRIPTION

FIG. 1 is a top, front, right perspective view of a foldable utility enclosure showing our new design;

FIG. 2 is a front elevational view thereof, which is identical to a rear elevational view;

FIG. 3 is a right side elevational view thereof, which is identical to a left side elevational view;

FIG. 4 is a top plan view thereof;

FIG. 5 is a bottom plan view thereof;

FIG. 6 is a front, right perspective view of the foldable utility enclosure in a folded conformation;

FIG. 7 is a front elevational view thereof, which is identical to a rear elevational view;

FIG. 8 is a right end elevational view thereof, which is identical to a left end elevational view;

FIG. 9 is a top plan view thereof; and,

FIG. 10 is a bottom plan view thereof.
